UNITED STATES PATENT OFFICE.

PETER M. CONKEY, OF LONGBEACH, CALIFORNIA

COOKER.

1,070,586.

Specification of Letters Patent. Patented Aug. 19, 1913.

Application filed July 1, 1912. Serial No. 703,984.

To all whom it may concern:

Be it known that I, PETER M. CONKEY, a citizen of the United States, residing at Longbeach, in the county of Los Angeles and State of California, have invented a new and useful Improvement in Cookers, of which the following is a specification.

The invention relates to cookers and especially to that class where the process is aided by the use of steam pressure.

Its principal object is to provide a cooker in which articles can be cooked in high altitudes and increase the temperature required to boil water contained and used as a cooking medium.

It is also an object to provide a cooker in which all the vapor or steam is confined and the heat absorbed by the contained articles.

It is a further object to provide means to regulate the pressure within the cooker and provide safety means in connection therewith.

In the drawings accompanying this specification and forming therewith a portion of the application for Letters Patent, Figure 1 is a central vertical section through the cooker, showing the closure and the auxiliary connections in elevation. Fig. 2 is a plan view of the device viewed from above. Fig. 3 is a cross section on the line 3—3 looking in the direction of the arrows, and Fig. 4 is a cross section on the line 4—4 viewed in the direction of the arrows.

Heretofore, in the preparing of foods by boiling processes in high altitudes, the time required has been materially increased on account of the reduced atmospheric pressure and the consequent absorption of an excess of heat units to reach the proper temperature at which water will boil under these circumstances.

I overcome the objections mentioned by the use of my invention and in the drawings 5 represents the cooker, preferably of cylindrical form composed of side walls 6 of heat resisting and pressure sustaining material. In the bottom of the cooker is shown at 7 a disk set inside the cylindrical walls and secured by the rivets 8 as is customary in steam boiler structure.

The top 9 is shown, preferably formed of cast metal, threaded on its engaging periphery and adapted to engage threads cut on the inner periphery of the cylindrical walls 6 to securely hold the same in relation thereto and form an air tight connection.

Concentrically placed in the top 9 is the entrance opening 10 beveled to form a seat for the valve lid 11 and adapted to register so as to form a tight seal. To properly secure this lid it is provided with an annular hub 12, which is threaded to receive the threaded stem 13, which passes therethrough and is supplied with the head 14 which engages with the locking bar 15 pivotally mounted on the same. The upper end of the valve stem is provided with a hand wheel 16 suitably keyed to the stem by the key 17.

In a threaded aperture, extending through the top 9 is placed the screw threaded nipple of a safety valve 18 of usual and common form, provided with a lever and weighted ball 19 which can be set to blow at any desired pressure. An aperture is provided in the side wall 6 in which is attached by suitable threaded connections the pressure gage 20, adapted to register the pressure within the cooker.

Suitably placed in proximity to the bottom is shown the drain cock 21 by means of which contained water, to any required amount may be withdrawn without disturbing any of the other connections.

As shown in Fig. 1, the device is placed on any suitable support as 22, on a heating member, shown as a gas burner 23.

Within the cooker is shown a plurality of small containers of such size as to be readily introduced or removed through the aperture 10 in the top of the cooker.

In the operation of the device, water is introduced after the containers 24 are placed in position, to a height that will approach near the tops of the containers. The valve lid 11 is approximated in position and the cross bar introduced to engage the lower lip of the openings and the hand wheel turned until the lid is firmly seated in the opening, when the device is ready to receive the application of heat.

As will be readily understood, as soon as the heat is applied the pressure will rise in the confined area of the cooker and will approximate more nearly the usual atmospheric pressure in lower altitudes, the water will boil and generate steam at the usual temperature of 212° F. and the articles in the containers 24 will receive the full benefit of the heat units generated and will lose no aromatic properties which are usually lost in open cooking, and, by retaining the pressure, the time required ordinarily in di-

rectly applying the heat will be materially reduced, approximately from two-thirds to one-fourth of the time, not only from the beneficial results from the pressure, but by 5 confining the heat units. Disagreeable odors frequently emanating from uncovered cooking articles are also eliminated by the use of my improved cooker.

What I claim is:

- 10 A cooker, comprising a cylindrical receptacle provided with a threaded external opening, a centrally apertured closure threaded on its periphery to engage the cylindrical receptacle, said aperture having inwardly inclined edges forming a valve seat, 15 a valve plate adapted to fit in said valve seat to form a closure therefor provided with

a centrally threaded bore, a threaded shaft engaging said threaded bore provided with a bar engaging lug, a bar of greater length 20 than the internal diameter of said valve seat mounted on said valve shaft, and a handle keyed to said threaded valve shaft, whereby the bar engaging said lower edge of the valve seat, the valve may be tightly seated 25 to retain pressure created within the receptacle.

In witness that I claim the foregoing I have hereunto subscribed my name this 22nd day of June, 1912.

P. M. CONKEY.
